UNITED STATES PATENT OFFICE

JOHN R. SMITH, OF LOS ANGELES, CALIFORNIA

SILENT JET, AIR-VENTING, REFILL TOILET BOWL

Application filed August 16, 1929. Serial No. 386,366.

This invention relates to water closet bowls of any standard or preferred type.

An object of the invention is to provide a toilet bowl incorporating means whereby to secure a constant volume of re-fill water; to effect a great reduction of the noise of jet action from flushing water; to facilitate the equal jet action all around the bowl rim so as to get a maximum volume of water into the bowl in the least time from start of spray, to eliminate travel of a mass of water in the rim to fill the rim all around for wash down shower at each flush; to maintain a constant supply of water in the rim at all times; to reduce the volume of air content in the rim as compared with types of rims with jet holes for wall jets, and to effect a removal of odorous air from the bowl by use of the flushing water entering the bowl.

More specifically an object is to provide a bowl having a jet rim provided with a water trough to retain water and thus displace so much air thereby effecting a reduction of jet noise as the flushing water fills the rim and overflows at the jet holes.

Also, to provide an air venting ejector or suction device utilizing the flushing water to effect an extraction of air from the bowl at a moment prior to the jet shower action.

And, further, to provide a reliable means for effecting a re-fill of the bowl with a substantially uniform volume of water.

Other objects, advantages and features of construction, combination, and details of parts and the method of action will be made manifest in the ensuing description of the herewith illustrative embodiment, it being understood that modifications, variations and adaptations may be resorted to within the spirit, scope and principle of the invention as it is more directly claimed hereinafter, and which consists of the method and apparatus hereof and the equivalent.

Figure 1 is a vertical, longitudinal section. Figure 2 is a horizontal section on line 2—2 of Figure 1.

The apparatus embodies a bowl 2 having a flushing rim 3 at the rear of which is a re-fill reservoir 4 receiving flushing water from a pressure supply pipe 5.

This pipe envelops the upper, open end of a downwardly convergent ejector nozzle 6 which is fixed in an ejector passageway 7 whose lower end passes beyond the basin 2^a and upward toward the siphon lip 2^b under the basin.

The bowl has the usual siphon down-leg 8.

The upper part of the passageway 7 opens under a hood 10 into the bowl space and when flushing water is turned on its high velocity jet causes a strong suction of air at its mouth; the inducted air and the water are forced over the water basin lip 2^b and thence to leg 8.

The rim 3 has a trough 3^a with divergent sides and this communicates freely with a well 11 which opens directly to the re-fill reservoir 4. The pipe 5 terminates above the level of the well top and quickly fills with water which backs up under resistance of the constant body of water in the trough 3^a and well 11, which are on a level.

Around the inner wall of the trough is a ledge 12 which has a series of vertical perforations 13 discharging against the face of the bowl all around.

The ejector nozzle 6 is in an inner wall ring 14 which keeps the trough water from flowing down the vent passageway 7.

It will be seen that there is but a small air space in the rim and this is principally to allow for expansion of ice should the water freeze in the trough; this being more or less V-shaped.

In operation of the apparatus the flush water rushes to the nozzle 6 and thence to the outlet 2^b and backs in the trough and in the reservoir until the jet openings are filled and the water forced out therethrough. The nozzle flow causes an induction of air at the mouth 10 from the bowl, this occurring a period just before jets flow from the rim holes 13.

When the supply water is stopped the backed supply passes down under air pressure in the reservoir until it falls to the level of the trough ledge and thus re-fills the bowl after the siphon action of the basin occurs.

What is claimed is:

1. In a bowl of the class described, a flushing rim with a substantially V-shaped trough

being imperforate at the bottom so as to hold water and an inner wall having a series of downward jet apertures from the trough.

5. In a bowl of the class described, a flushing rim with a substantially V-shaped water holding trough and an inner wall having a series of downward jet apertures from the top of the trough, and a re-fill reservoir connected to the rim trough.

10. 3. In a bowl of the class described, a flushing rim with jet apertures, and a re-fill reservoir communicating with the rim space and filling the bowl with re-fill water through the rim.

15. 4. In a bowl of the class described, a flushing rim with jet apertures, and a re-fill reservoir communicating with the rim space, and an ejector tube leading from said reservoir to the siphon passage of the bowl independently of the rim, and an air eduction mouth to the tube from the bowl.

20. 5. In a bowl of the class described, a flushing rim with jet apertures, and a re-fill reservoir communicating with the rim space, and an ejector tube leading from said reservoir to the siphon passage of the bowl independently of the rim, and an air eduction mouth to the tube from the bowl, and a water supply means leading to said tube and to said reservoir.

25. 6. In a bowl of the class described, a flushing rim, and a communicating re-fill reservoir, an ejector tube, a water supply means opening toward the bottom of the reservoir, and a nozzle embraced by the said means and leading into said tube.

30. 7. In a bowl of the class described, a flushing rim and a basin washed thereby, an ejector passageway, to the basin, having its mouth in communication with and adjacent to the rim chamber, and a water supply pipe which terminates close, and in axial relation, to the said mouth so that a space is left for flow of water to the rim; whereby water is in principal part supplied to the passageway before the rim flow is fully effective.

35. 8. In a bowl of the class described, a flushing rim and a basin washed thereby, an ejector passageway, to the basin, having its mouth in communication with and adjacent to the rim chamber, and a water supply pipe which terminates close, and in axial relation, to the said mouth so that a space is left for flow of water to the rim; whereby water is in principal part supplied to the passageway before the rim flow is fully effective, and a nozzle whose intake end is disposed in, and in spaced relation to, the pipe end and leaving a passage to the rim chamber and which nozzle enters the mouth of the passageway.

40. JOHN R. SMITH.
